COMBINED LOCATING AND MARKING GAUGE FOR JUNCTION BOXES

Herschel L. Sunley, 1804 Whittier Ave.,
Springfield, Ill. 62704

Filed Aug. 23, 1972, Ser. No. 282,928

Term of patent 14 years

Int. Cl. D10—04

U.S. Cl. D52—6 R

FIG. 1

FIG. 3

FIG. 2

FIG. 4

FIG. 5

FIG. 1 is a perspective view of a combined locating and marking gauge for junction boxes showing my new design;

FIG. 2 is a top plan view of FIG. 1;

FIG. 3 is a side elevational view of FIG. 2;

FIG. 4 is a bottom plan view of FIG. 2; and

FIG. 5 is a lower end elevational view of FIG. 2.

The locating pins in all views are shown broken-away to show indeterminate length.

I claim:

The ornamental design for a combined locating and marking gauge for junction boxes, as shown and described.
